ROBERT C. COLE, OF HARTFORD, CONNECTICUT, ASSIGNOR TO THE JOHNS-PRATT COMPANY, OF HARTFORD, CONNECTICUT, A CORPORATION OF CONNECTICUT.

CARTRIDGE-FUSE.

1,396,731.

Specification of Letters Patent.

Patented Nov. 15, 1921.

Application filed January 24, 1920. Serial No. 353,752.

To all whom it may concern:

Be it known that I, ROBERT C. COLE, citizen of the United States, residing at Hartford, in the county of Hartford and State 5 of Connecticut, have invented a new and useful Improvement in Cartridge-Fuses, of which the following is a specification.

This invention relates to the construction of non-renewable cartridge fuses of the 10 knife blade type.

The object of the invention is to provide a casing for a fuse of this class comprising parts which are simple to make and easy to put together, and which when once assembled 15 cannot be taken apart or entered without special tools and the destruction of or irreparable damage to essential elements.

This object is attained by locking the 20 knife blades with key plates so shaped that when fitted together they close the ends of the tube, and which have lugs that slide into and fit undercut mortises in the ends of the tubes, and holding the key plates in place by the caps which engage with the edges of the 25 lugs so that the caps cannot be removed after once being set without destruction or damage.

Figure 1 of the accompanying drawings shows a side view of a knife blade fuse constructed 30 according to this invention with one half cut in central section. Fig. 2 shows an edge view with one of the caps broken away. Fig. 3 shows a section of the tubular casing. Fig. 4 shows a transverse section on the 35 plane indicated by the dotted line 4—4 on Fig. 1. Fig. 5 shows a face view of one of the lock plates. Fig. 6 shows an edge view of the lock plate. Fig. 7 shows a face view of one of the caps. Fig. 8 shows a section 40 of the cap.

The body of the casing consists of a tube 1 of fiber or other suitable insulating material. In each end of the tube diametrically opposite each other two dove-tail or undercut mortises 2 are punched or otherwise formed. The terminal blades 3 are formed 45 of copper in the usual manner and are connected inside of the casing by any type of fusible link 4. On each blade just inside of the end of the tube a plate 5 is secured in such manner as to provide recesses 6 at the 50 end of the tube between the inner edges of the wider part of the blade and the plate. These recesses could be, of course, made any desirable depth by simply cutting away

more or less of the edges of the wider sections of the blades. Each end of the tube is closed by a pair of key plates 7, each plate being substantially semi-circular and having a slot 8 that fits the blade and a dove-tail 60 lug 9 designed to enter a dove-tail mortise in the end of the tube. These key plates are thrust together on the blades from opposite sides over the ends of the tubes, and when each pair is completely together and the 65 ends of the tube are closed thereby the dove-tail lugs lie in the dove-tail mortises in the tube so that the key plates cannot move lengthwise of the tube. After these parts are in position the caps 10 with slots 11 that 70 just fit the blades are slipped over the blades and onto the ends of the tube over the key plates. When in place the caps hold the key plates from moving transversely and unlocking the blades. After the caps have been put 75 in place their inner edges may be spun down over the ends of the key plate lugs or the caps may be provided with internal shoulders 12 at their inner edges and the key plates so formed that when assembled the 80 lugs may project beyond the surface of the tube, then when the caps are slipped on, the lugs will yield until after the caps have reached their closing position, at which 85 time the lugs will be free to spring outward slightly and engage the shoulders around the inner edges of the caps and thus prevent the caps from withdrawal.

With this construction the caps hold the 90 key plates from radial displacement and cover the joints between the key plates, and the key plates with their lugs entering the dove-tail mortises in the tube prevent the blades from rotating and from moving longitudinally inward or outward of the tube. 95 It is preferred to make the key plates of very hard metal so that it will be difficult for anyone to drill a hole through them for the purpose of inserting a conducting wire. This construction is very easy to assemble 100 and yet it is very difficult to take apart, or to restore it after the fuse link is once blown without visible indication of the fact that the casing has been tampered with. The casing may or may not be filled with the 105 usual condensing and absorbing materials.

The invention claimed is:—

1. A cartridge fuse comprising a tubular insulating casing having undercut mortises in its ends, contact terminals extending 110

through the ends of the casing, a fusible link connecting the terminals within the casing, key plates engaging the terminals and having lugs fitting the mortises in the ends of the casing, and caps thrust upon the ends of the casing over the key plates and held against removal thereby.

2. A cartridge fuse comprising a tubular insulating casing having undercut mortises in its ends, contact terminals extending through the ends of the casing, a fusible link connecting the terminals within the casing, key plates engaging the terminals and having lugs fitting the mortises in the ends of the casing, and caps thrust upon the ends of the casing over the key plates and holding the plates against transverse displacement, said caps having their inner edges extending diametrically inward over the inner ends of the key plate lugs and held on the casing thereby.

3. A cartridge fuse comprising a tubular insulating casing having undercut mortises in its ends, contact terminals extending through the ends of the casing, a fusible link connecting the terminals within the casing, key plates engaging the terminals and having lugs fitting the mortises in the ends of the casing, and caps thrust upon the ends of the casing over the key plates and holding them against removal and being held against removal thereby.

4. A cartridge fuse comprising a tubular insulating casing having dove-tail mortises in its ends, contact terminal blades extending through the ends of the casing, key plates engaging the terminal blades and having dove-tail lugs fitting the mortises in the ends of the casing, and caps having slots fitting the terminal blades slipped longitudinally upon the ends of the casing and holding the key plate lugs in the mortises in the tube.

5. A cartridge fuse comprising a tubular insulating casing having undercut mortises in its ends, contact blades with recesses in their edges extending through the ends of the casing, key plates fitting the recessed sections of the blades and having lugs fitting the mortises in the ends of the casing, and caps having slots fitting the terminal blades slipped longitudinally upon the ends of the casing over the key plates and holding the

plates against transverse displacement and held from longitudinal displacement thereby. 55

6. A cartridge fuse comprising a tubular insulating casing having undercut mortises in its ends, contact blades extending through the ends of the casing, anchor plates fastened on the blades within the casing, key plates engaging the blades outside of said anchor plates and closing the ends of the casing, said plates having lugs fitting the mortises in the ends of the casing, and caps thrust upon the ends of the casing and formed inward over the key plate lugs. 60 65

7. A cartridge fuse comprising a tubular insulating casing having undercut mortises in its ends, contact blades extending through the ends of the casing, anchor plates fastened on the blades within the casing, semi-circular key plates fitted together and closing the ends of the casing about the blades outside of said anchor plates, the joints between said key plates being covered within 70 75 by said anchor plates, lugs extending at substantially right angles from the key plates and fitting the mortises in the ends of the casing, and caps having slots fitting the blades thrust longitudinally upon the ends of the casing over the key plates and holding the key plates against transverse displacement.

8. A cartridge fuse comprising a tubular insulating casing, contact terminals extending through the ends of the casing, key plates engaging the terminals, said plates holding the terminals from longitudinal movement inward and outward of the casing and being held by the casing from movement longitudinally of the casing, and caps having slots fitting the terminals thrust upon the ends of the casing, said caps and key plates coöperating to secure all of the parts together. 85 90

9. Means for retaining a knife blade fuse terminal in a casing, comprising key plates in engagement with the casing and held thereby from movement longitudinally of the casing and in engagement with the blade and thereby holding the blade from movement longitudinally of the casing, and a cap located on the end of the casing over the key plates and holding them in place and held against removal thereby. 95 100

ROBERT C. COLE.
